UNITED STATES PATENT OFFICE.

IRA EVERETT, OF SAYRE, PENNSYLVANIA, ASSIGNOR, BY MESNE ASSIGNMENTS, TO
KENNOWAY MANUFACTURING COMPANY, A CORPORATION OF DELAWARE.

CAR-ROOF CONSTRUCTION.

Original application filed October 16, 1917, Serial No. 196,939. Divided and this application filed May 27,
1918. Serial No. 236,914.

To all whom it may concern:

Be it known that I, IRA EVERETT, a citizen of the United States, and a resident of Sayre, in the county of Bradford and State of Pennsylvania, have invented certain new and useful Improvements in Car-Roof Constructions, of which the following is a specification.

My present invention relates to improvements in car framing construction, and more particularly the construction of end framing for box cars.

The principal objects of my present invention are to provide improved means for bracing the roof and end of a car; the provision of improved means for preventing shifting of the roof; the provision of improved means for preventing longitudinal shifting of the roof boards; the provision of improved means for preventing longitudinal shifting of the ridge pole and purlins; the provision of improved means for connecting the end posts to the end plate; the provision of an improved form of end plate; the provision of improved means for supporting the ridge pole, purlins and roof boards; the provision of improved means for connecting the end posts to the roof of the car; the provision of an improved form of diagonal brace arranged internally and horizontally of the car; the provision of improved means for connecting the end posts and diagonal end braces to the end sill; the provision of an improved shoe sill; the provision of an improved end post adapted to receive the ends of an end post and a diagonal brace, and generally to improve, simplify and cheapen the construction of car ends and framing therefor. This application is a division of Serial No. 196,939, filed October 16, 1917.

In attaining these and other objects and advantages, to be hereinafter set forth, I have provided a construction, one embodiment of which is illustrated in the accompanying drawings, in which:

Figure 1 is an end view of a car constructed in accordance with my present invention;

Figure 2 is a vertical longitudinal section on the line 2—2 of Figure 1;

Figure 3 is a plan view of the car end with the roofing plates removed;

Figure 4 is a front view of one of the shoes for the end posts and end braces; and,

Figure 5 is a plan view of the same.

The car framing illustrated in the drawings comprises end posts 10, corner posts 11, end sill 12, end plate 13, side plates 14 and sheathing 17.

The end plate 13 is formed of metal, preferably steel, and is provided with an inwardly directed lower flange 14 and an outwardly directed upper flange 15. This upper flange 15 is of the same slope as the roof and acts as a support for roof boards 16, which are bolted to this flange.

The lower flange 14 is secured to the end posts 10 by means of brackets 18. Above the flange 14 is arranged a wooden end plate 19, which not only supports the sheathing 17 on its inner vertical face, but also carries the ridge pole 20 and the purlins 21 on its upper edge. One of the principal advantages of this construction is that it prevents shifting of the roof by reason of the fact that the roof boards are bolted to the upper flange of the end plate which prevents longitudinal displacement of the roof boards and also by reason of the fact that ends of the ridge pole and purlins rest against the inner face of the end plate which prevents longitudinal movement of the ridge pole or purlins.

Another advantage of the form of construction is that the metallic end plate 13 protects the wooden end plate 19 from the weather, and the outwardly projecting upper flange 15, in conjunction with the roof boards, form eaves which tend to protect the end of the car from rain and snow. The lower flange 14 provides suitable means for indirectly connecting the wooden end plate 19 to the metallic end posts 10.

The use of two end plates, both of the same slope as the roof, enable both the ridge pole 20 and purlins 21, as well as the roof boards 16, to be adequately supported.

Carried by the roof boards 16 is the usual running board 22.

The purlins 21 are supported intermediate the ends of the car by carlines 23 carried by the side plates 14^a.

The side plates and end plates 19 and 13 are connected by diagonal tie members or braces 24. These tie members are secured to the side plates 14^a by brackets 25 bolted 10 to the inner face of the side plates. The members 24 are connected to the end plates by a bracket 26, which is clamped to both end plates by means of bolts 27, which also serve to hold the wooden end plate 19 in 15 position relative to the metallic end plate 13.

These brackets protect the car end from shocks and blows from the inside against the car and due to movement of the load within the car.

20 It will be observed that all longitudinal outward strains are carried by the externally arranged metallic end plate and end posts.

25 In order to prevent the sides of the car bulging intermediate the end plate and end sill, a tie rod 40 is provided, which is arranged in an internal rabbet or groove 41 in the end sheathing of the car.

30 The car is further strengthened by means of diagonal braces 28, extending between the end posts 10 and the corner posts 11. The end posts 10 and the braces 28 are of angular, preferably of Z-shaped, cross section with one flange bolted to the sheathing 17 at 29. 35 The corresponding flanges of adjacent end posts and braces are arranged to extend in opposite directions from the webs of these parts in order to simplify the construction of the shoe or bracket 30 by which the end 40 posts and braces are connected to the end sill 12.

45 This shoe 30 comprises a base portion adapted to be bolted to the upper surface of the end sill and an upwardly projecting portion 31 adapted to be secured to the ends of the end posts and end braces. Against the central part 32 of this projection bear the inner flanges of both end post and brace, while the web of these parts bear against the forwardly extending parts 33 and 34 of this projection. The outer flange of the end post bears against the part 35 of the projection 31.

50 Apertures 37 are provided for the bolts or rivets which secure the ends of the end post and brace to the projection 31.

55 From inspection of Figure 5 it will be seen that by arranging corresponding flanges at the end post and brace to turn in opposite directions, only one projection of general U-shape form is required, instead of two projections both of Z-shaped cross-section.

60 The ends of the braces and end posts bear against the inner faces of the projection 31, so that outward strains and shocks are trans-

mitted to the shoe independently of the bolts or rivets which connect these parts.

The upper ends of the braces 28 are connected to the lower flange 14 of the end plate 13 by triangular brackets 38. 70

Having thus described my invention and illustrated its use, what I claim as new, and desire to secure by Letters Patent is:

1. A car framing construction comprising, in combination, an external metallic end 75 plate, an internal wooden end plate, two side plates and diagonal tie members connecting both end plates to said side plates.

2. A car framing construction comprising an external metallic end plate, and an internal wooden end plate secured together, 80 a side plate, a bracket secured to both end plates, and a diagonal brace connecting said bracket to said side plate.

3. A car framing construction comprising, 85 in combination, a metallic end plate, a wooden end plate attached to the inner face thereof, and longitudinal roof members supported by said wooden end plate.

4. A car framing construction comprising, 90 in combination, side plates, a wooden end plate, a metallic end plate externally arranged with respect to the wooden end plate, a bracket secured to the inner vertical face of said wooden end plate and tie members 95 between said bracket and said side plates.

5. A car framing construction comprising, 100 in combination, side plates, an end plate and diagonal tie members between said side plates and said end plate, the points of attachment of said tie members to said end plate being located adjacent to the center lines of said plate in the vertical and horizontal planes.

6. A car end framing construction comprising, 105 in combination, a ridge pole and purlins, and a metallic end frame, against which the contacting ends of said ridge pole and purlins abut and thereby preventing shifting of the roof. 110

7. A car end framing construction comprising, 115 in combination, a ridge pole and purlins, and a metallic end plate against which the contacting ends of said ridge pole and purlins abut and thereby preventing shifting of the roof.

8. A car end framing construction comprising, 120 in combination, carlines, purlins, and roof boards and a metallic end plate rigidly connected to said roof boards, said carlines, purlins and roof boards abutting against said end plate, to prevent shifting of the roof.

9. A car end framing construction comprising, 125 in combination, side plates, purlins, an end plate abutting against the ends of purlins, and diagonal braces between said side plates and said end plate to prevent shifting of the roof.

10. A car end framing construction com-

prising, in combination, a metallic end plate, a wooden end plate attached thereto, longitudinal roof members supported by said wooden end plate and contacting at their ends with said metallic end plate and roof boards rigidly connected to said metallic end plate, whereby shifting of the roof is prevented.

11. A car framing construction compris-

ing, in combination, an external metallic end plate, and an internal wooden end plate, secured together, two side plates, and diagonal tie members connecting both end plates to said side plates.

In testimony whereof, I have hereunto signed my name.

IRA EVERETT.
